COVER FOR LARGE BOOKS

Maynard R. Hultman and Carl E. Hultman,
Crafton, Pa.

Application January 12, 1942, Serial No. 426,516

2 Claims. (CL. 281—37)

This invention relates to covers for large books, especially public record books, such as deed and mortgage books, but is not limited to this type alone.

An object of the invention is to provide a cover formed of ply wood recessed at the rear edge to receive the leaves of the hinge and clamp strips to cover the leaves, the recesses being stepped so that the strips are flush with the surfaces of the ply wood cover and thus the book will be of uniform thickness without projecting edges at the hinge.

A further object is to provide a device of this character in which the use of ply wood eliminates seasoning after the book is finished and also warping of the cover as well as distortion of the cover at the hinge will be positively prevented.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a perspective view of a ply wood book cover showing the hinge leaf and clamp strip, constructed in accordance with the invention.

Figure 2 is a longitudinal sectional view showing the ply wood cover provided with stepped recesses at the rear edge to receive the hinge leaf and clamp strip.

Figure 3 is a fragmentary cross sectional view taken on the line 3—3 of Figure 1.

Figure 4 is a detail cross sectional view showing the ply wood cover having a bevel at the notched rear edge so that the clamp strip and leaf are recessed below the surface of the cover.

Figure 5 is a plan view of the hinge leaf.

Referring now to the drawing in which like characters of reference designate similar parts in the various views, 19 designates a book cover formed of ply wood or similar material, preferably fabricated of three layers or plies. The rear longitudinal edge of the cover is provided with stepped recesses 11 and 12, the former being of a depth equal to the uppermost ply or layer, and

the latter being of a depth equal to about three-fourths of the thickness of the intermediate ply or layer, as best shown in Figure 2. A plurality of openings 13 are formed in a longitudinal row and open through the lowermost step or recess 12 and through the bottom ply of the cover to receive pins 14.

A metal hinge leaf 15 of the type used in the hinges of large ledgers and books, is received in the lowermost step or recess 12 and is of sufficient thickness to be flush with the intermediate ply of the cover, as best shown in Figure 3. The hinge leaf is rolled upon itself at the rear longitudinal edge to provide a tube 16 for receiving a hinge pintle, not shown, the tube having notches 17 at intervals and having extensions 18 at the ends to coat with the companion hinge structure of conventional backs of large heavy volumes. The hinge leaf is provided with a longitudinal row of openings 19 to receive the pins 14. A clamp strip 20 is superposed upon the hinge leaf and is of the same thickness as the uppermost ply of the cover, and is of sufficient width to fill the step or recess 11 and overlap the hinge leaf. The rear longitudinal edge of the clamp strip extends flush with the rear longitudinal edge of the cover. The clamp strip is provided with a longitudinal row of openings 21 to receive the pins 14. The upper surface of the clamp strip extends flush with the upper surface of the uppermost ply of the cover so that the entire cover and hinge assembly is of uniform thickness throughout, as best shown in Figures 1 and 3.

In Figure 4 is shown a modified form of the device in which the uppermost step or recess 22 is provided with a bevel 23 on the longitudinal inner edge and the clamp strip 24 is only of sufficient thickness to extend with its top surface flush with the bottom of the bevel when received in the step or recess 22. Thus, the hinge portion of the cover is of less thickness than the remainder of the cover. This being the only difference between the modified form of the invention and the first described form of the invention, a description of the other parts constituting the hinge need not be repeated.

From the above description it is thought that the construction and operation of the invention will be fully understood without further explanation.

What is claimed is:

1. In book covers, a cover member formed of ply wood fabricated of three plies, the rear longitudinal edge being provided with a pair of stepped recesses, one of the recesses being of a depth

equal to the thickness of the uppermost ply and the other being of a depth equal to about three-fourths of the thickness of the intermediate ply, the lowermost ply being unrecessed, a metal hinge leaf received in the recess of the intermediate ply, a clamp strip received in the recess of the uppermost ply and overlapping the hinge leaf to the rear longitudinal edge of the cover member, and securing means passed through the clamp strip, the hinge leaf and the unrecessed ply of the cover member.

2. In a book cover, a cover member formed of

three plies, the three longitudinal edges provided with a pair of stepped recesses, the center ply having a recess equal to about three fourths of the thickness thereof, a metal hinge leaf received in the recess of the center ply and having its upper face flush with the upper face thereof, and a clamping strip in the recess of the upper ply and flush with the upper face thereof and overlapping the hinge leaf to the rear longitudinal edge of the lower ply.

MAYNARD R. HULTMAN.
